UNITED STATES PATENT OFFICE.

CLARENCE A. SNOW, OF NEWTON, IOWA, ASSIGNOR TO THE MAYTAG COMPANY, OF NEWTON, IOWA, A CORPORATION OF IOWA.

MOLDING APPARATUS.

1,371,447.

Specification of Letters Patent. Patented Mar. 15, 1921.

Application filed July 27, 1918. Serial No. 246,956.

To all whom it may concern:

Be it known that I, CLARENCE A. SNOW, a citizen of the United States, residing at Newton, in the county of Jasper and State 5 of Iowa, have invented new and useful Improvements in Molding Apparatus, of which the following is the specification.

This invention relates to apparatus for use in forming molds in sand or the like and 10 more particularly to the withdrawal of the gate patterns therefrom.

Among the objects of my invention is to make possible the easy, safe, and rapid withdrawal of the gate patterns for connecting 15 the runner with the casting, after the same has been rammed or tamped in the mold; further to attain the foregoing object in connection with the form of gates known as "horn gates"; further to provide apparatus 20 in which the gate patterns are caused to move in the arc of a circle to eliminate all danger of tearing the sand in withdrawing the gate patterns; further to effect the simultaneous withdrawal of a plurality of gate patterns 25 by the single operation of a handle; further to return all of the gate patterns to their operative position by a mere reverse operation to that last mentioned; further to provide a more simple, efficacious, and economi- 30 cal apparatus; and such further objects, advantages and capabilities as will later more fully appear.

My invention further resides in the combination, construction and arrangement of 35 parts illustrated in the accompanying drawings, and while I have shown therein a preferred embodiment I desire it to be understood that the same is susceptible of modification and change without departing from 40 the spirit of my invention.

In the drawings:

Figure 1 is a perspective view of the upper side of a match plate embodying my invention.

Fig. 2 is a vertical transverse sectional view of Fig. 1 and showing a portion of the support for the match plate.

Fig. 3 is a detail view showing the arrangement for transmitting rotation from 50 one shaft to the other.

Fig. 4 is a plan view of the match plate for forming the drag or lower half of the mold.

Fig. 5 is an edge elevation of Fig. 4.

Fig. 6 is a vertical transverse section 55 through Fig. 4.

As is well known in the art of molding the mold may be formed upon the opposite sides of a single match plate, the two halves of the mold fitting together upon the withdrawal of the match plate and patterns; or the cope may be formed upon one match plate and the drag upon another, after which the two halves of the mold will be put together. I have illustrated my invention as 60 applied to a match plate of the latter class, the match plate for the cope being illustrated in Figs. 1 and 2, and the match plate for the drag half of the mold being illustrated in Figs. 4 to 6.

As shown in Figs. 4 to 6 the match plate for forming the drag is designated at 1, and has secured thereto a suitable pattern 2 for forming the runner in the mold. The plate 1 is also provided in the usual manner with 70 a plurality of openings 3, within which are embedded to the proper depth the patterns 4 for forming the lower half of the mold. After the sand is suitably rammed or tamped in the drag and the drag and match plate 1 75 rolled over upon the bottom board, the plate 1 is then removed and the patterns withdrawn. 5 designates suitable pins secured to the plate 1 to properly position the ears of the drag.

Referring now to Figs. 1 and 2, it will be seen that the match plate for forming the cope or top half of the mold comprises the plate 6 provided with suitable means such as the aperture 7, and the shoulder 8 for 90 properly positioning and maintaining the cope portion of the flask thereon. The match plate 6 is also provided in the usual manner with the recesses 9, within which are seated the patterns 10 to a depth sufficient to form 95 the proper parting. The patterns are also provided with suitable core prints 10' and 11. The plate 6 is also provided with a plurality of apertures 12, through which extend horn gate patterns 13 and 13'. As 100 seen in Fig. 2, these horn gate patterns are provided at their lower portions with the arms 14 and 14', which are rigidly secured by means of the hubs 15 and 15', upon the shafts 16 and 17 respectively. While I have 105 shown the end of the horn gate patterns as being in contact with the top portion of the pattern 10, it is to be understood that they

are merely resting against the same, so that upon proper movement of the horn gate patterns they will move away therefrom. The shafts 16 and 17 are mounted for rotation in the match plate 6, and the shaft 16, as shown in Fig. 1, is extended to reach beyond the end of the match plate and upon which outer end is rigidly secured the handle 18. Upon the opposite end of the shaft 16 is keyed or otherwise suitably secured a fan gear 19, which meshes with the similar fan gear 20 secured upon the shaft 17, in order to transmit rotation, but in an opposite direction to shaft 17. The horn gate patterns 13 and 13' are formed in the arc of a circle whereby upon suitable rotation of shafts 16 and 17 they will be withdrawn from the sand of the mold, which has been tamped therearound, and caused to pass downwardly through the apertures 12.

The operation of my improved device is as follows: The drag half of the mold is formed upon the match plate illustrated in Figs. 4 to 6, and completed in an appropriate manner, it having formed therein the runner depression by virtue of the runner pattern 2 secured to match plate 1. After completion of the lower half of the mold the upper half is then formed on match plate 6 shown in Figs. 1 and 2. It is here pointed out that the larger ends of the horn gate patterns 13 and 13' are in approximate alinement, so that after the top half of the mold is completed and placed upon the bottom half these larger ends of the horn gate patterns will fall just above the runner depression formed in the lower half of the mold, into which runner the molten metal will be conducted through a sprue opening formed in the usual manner. It is of course, understood that prior to filling in the sand for the upper portion of the mold that the horn gate patterns will be swung into the position illustrated in Fig. 1. After the sand is suitably tamped or rammed in the upper half of the mold the handle 18 will be raised, thus swinging the horn gate patterns 13 downwardly into the position, as indicated by dotted lines in Fig. 2, thus entirely removing these gate patterns from the sand of the mold and leaving a passageway which, when the pattern is removed from the mold, will conduct the hot metal from the runner into the mold cavity. By virtue of the engagement between the fan gears 19 and 20 the downward movement of the horn gate patterns 13 will be accompanied by a similar downward movement of the horn gate patterns 13', as will be clearly seen from the drawing.

While I have illustrated and described my improved device for removing gates as being applied in the construction of the upper half of the mold, it is obvious that the same may be equally well applied in the

formation of the lower half of the mold, if desired.

Having now described my invention, I claim:

1. In apparatus of the class described a plate having a plurality of apertures therein and adapted to have mounted thereon at a distance from each aperture a pattern, a horn pattern gate mounted in each of said apertures for movement therethrough, and means for simultaneously withdrawing said patterns through said apertures, said gate patterns being adapted to contact with said first named patterns. 70

2. In apparatus of the class described a plate having a plurality of apertures therein, a shaft rotatably associated with said plate, and a plurality of horn gate patterns rigidly mounted on said shaft and adapted to move through said apertures upon rotation of said shaft, and means to rotate said shaft. 80

3. In apparatus of the class described a plate having a plurality of apertures therein, a pair of parallel shafts rotatably mounted on said plate, a plurality of horn gate patterns secured to each of said shafts and adapted for movement through said apertures upon rotation of said shafts, and means for rotating said shafts whereby to 95 simultaneously withdraw all of said patterns through said apertures. 90

4. In apparatus of the class described a plate having a plurality of apertures therein, a pair of parallel spaced shafts rotatably mounted on said plate, a plurality of horn gate patterns secured to each of said shafts and adapted for movement through said apertures, means for rotating one of said shafts, and means for transmitting rotation 100 from said last mentioned shaft to the other shaft whereby to simultaneously withdraw said patterns through said apertures. 105

5. In apparatus of the class described a plate having a plurality of apertures therein, a horn gate pattern mounted in each of said apertures for movement therethrough, that portion of said horn gate patterns adapted to extend through said apertures being curved substantially on the arc of a circle, a shaft rotatably mounted on said plate, and arms rigidly connecting the curved portion of the horn gate patterns with said shaft whereby upon rotation of said shaft said horn gate patterns will be 115 moved through said apertures. 120

6. In apparatus of the class described a plate adapted to have mounted thereon a pattern, said plate having an aperture therein spaced from said pattern, a gate pattern mounted for movement through said aperture and adapted to contact with said pattern, and means for causing said gate pattern to move through said aperture toward and away from said pattern. 125

7. In apparatus of the class described a plate having a plurality of apertures therein, a pair of shafts rotatably mounted thereon, a plurality of horn gate patterns secured to each of said shafts and adapted to rotate therewith, said gate patterns being mounted for movement in either direction through said apertures, a handle on one of said shafts for rotating the same, and a gear on each of said shafts adapted to intermesh whereby movement of said handle

will cause simultaneous rotation of said shafts and a corresponding movement of said gate patterns through said apertures.

In witness whereof, I hereunto subscribe 15 my name to this specification in the presence of two witnesses.

CLARENCE A. SNOW.
